UNITED STATES PATENT OFFICE.

ADALBERT KURZWERNHART, OF ZUCKMANTEL, NEAR TEPLITZ, AUSTRIA-HUNGARY.

SIEMENS REGENERATIVE FURNACE.

No. 809,067.

Specification of Letters Patent.

Patented Jan. 2, 1906.

Application filed March 16, 1905. Serial No. 250,408.

To all whom it may concern:

Be it known that I, ADALBERT KURZWERNHART, a subject of the Emperor of Austria-Hungary, residing in Zuckmantel, near Teplice, Bohemia, Austria-Hungary, have invented certain new and useful Improvements in Siemens Regenerative Furnaces; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

This invention consists in certain improvements in Siemens regenerative furnaces having for their object to provide means for utilizing waste gas or products of combustion or other gases to force the combustible gas into the furnaces.

It has already been proposed in Siemens regenerative furnaces to force the gas remaining in the regenerative chamber before the reversal of the gas and air currents into the furnace by air, an inlet for which is provided at a suitable point and to there consume it. This, however, has the disadvantage that a small quantity of explosive mixture can and often does form at the point of meeting of the air and gas, which is of course not desired in the practical working of the apparatus and which is only discovered upon the starting of the flame. I have discovered that by using waste gas, smoke, and other products of combustion instead of air to remove the combustible gas in the gas-regenerative chamber the formation of explosive mixtures can be overcome.

In a copending application, Serial No. 206,098, filed May 3, 1904, I have described and claimed the method involved.

The present invention is an apparatus whereby that method can be carried out.

In the accompanying drawings, wherein my apparatus is fully illustrated in several forms thereof, Figure 1 shows the regenerative apparatus of a Siemens furnace in horizontal section. Figs. 2 and 3 are vertical sectional views of two arrangements of apparatus in which a blower or fan is employed to cause the waste gases and products of combustion in the flue to displace the gases in the regenerative chambers. Fig. 4 is a ver-

tical sectional view of an arrangement in which instead of using a fan, which simultaneously produces a suction and compresses a gasometer which acts by alternately forming a suction and compressing, is employed. Fig. 5 is a modification of what is shown in Fig. 4 involving the use of more than one gasometer. Fig. 6 shows an arrangement in which a steam or other fluid injector is employed instead of a fan, this arrangement working on the same principle as that shown in Figs. 2 and 3; and Figs. 7 and 8 show arrangements whereby the smoke and other products of combustion in the flue are withdrawn by a suitable suction means, such as the draft of the chimney, being replaced by air from outside.

In Fig. 1 is shown the regenerator apparatus of a Siemens furnace and the valve for regulating the gas and air flow. 1 and 4 are the two air-regenerative chambers, and 2 and 3 the two gas-regenerative chambers. 5 is a vertical passage for supplying the gas. 6 is the air-admission port; 7, the gas-controlling valve; 8, the air-controlling valve; 9, the smoke-flue, and 10 and 11 and 10' and 11' the channels affording communication between the valves 7 and 8 and the several regenerative chambers. In the position of the valves shown in this figure chamber 1 is filled with air and chamber 2 with gas. Chambers 3 and 4 are filled with combustible gases. If the valves are reversed, (turned into the dotted-line positions,) gas and air would flow through chambers 3 and 4, respectively, and the air and gas contained in chambers 1 and 2, respectively, would escape into the flue 9. By the present invention means is provided whereby before the reversing smoke or waste gas follows into the regenerative chambers filled with combustible gases.

Referring first to Fig. 2, the smoke-flue 9 is connected with a blower or fan 14 by a pipe 12, which discharges into the gas-supply pipe 5. 15 is a valve which is inserted in the pipe 12 between the fan and the point of discharge of said pipe 12 into pipe 5. This pipe is normally closed, so that during the normal action of the furnace no gas can flow from the gas-supply pipe 13' through the fan and pipe 12 into the flue. This valve can be self-acting, so that when the fan is out of operation it will close of its own weight. 13 is a valve

in pipe 13', which is shut off when the fan is operating. If now before the reversing-valve 13 is closed and 15 opened and the fan then set into operation, the smoke or waste gas in 5 the flue 9 would be drawn out therefrom and pressed into the gas-regenerative chamber. The fan should continue in action until all the gas forced out of the regenerative chambers in this way is consumed.

10 Referring to Fig. 3, instead of the two valves 13 and 15 a single valve can be used to shut off the flow of gas and simultaneously permit the discharge of the fan into passage 5, or vice versa.

15 Referring to Fig. 4, there is here used a means which alternately draws the smoke out of the flue and then forces it into the regenerative chamber instead of simultaneously forming these two functions as in the 20 case of the fan above described. Here a bell 17 is immersed, inverted, in water, being controlled as to its position by a counter-weight 18. The pipe 12 may be said to lead through the bell 17, a portion thereof being 25 removed within the bell. The part of the pipe which leads through the flue 9 into the bell is controlled at its discharge end (within the bell) by an upwardly-open valve 19. The part of said pipe 12' which leads from the 30 bell to passage 5 is controlled by valve 20, opening in relatively the same direction as valve 19. By this arrangement the contents of the flue 9 can be drawn into the bell by 35 raising the bell between the reversing periods, and then just before a reversing it can be lowered to force the gas in the bell past the valve 20 into the passage 5. The cubical contents of such a bell should therefore be as 40 large as that of the regenerative chambers, exclusive of the bricks inclosed therein.

As shown in Fig. 5, instead of one bell two 45 bells 21 and 22 may be used, being connected by a lever 23, so that when one rises the other falls.

45 In Fig. 6 as a simultaneous suction and force contrivance an injector 34 of steam, air, or other fluid can be used, drawing smoke from the flue 9 and forcing it into the passage 5, the same as in those forms already 50 described.

It will be understood that where there is more than one furnace in operation it is possible to have a common means for drawing out the smoke from their various flues and 55 forcing it into their regenerative chambers to replace the combustible gases therein contained.

In Figs. 7 and 8 a portion of the flue is 60 temporarily cut off from what continues to be the flue proper, and the smoke in the former is drawn out therefrom, forced through the regenerative chamber, ultimately discharging from the flue proper. To the smoke-passage 24 is connected the smoke-channel 9, which is divided into two parts 25

and 26. The portion 25 is of such size as to maintain a sufficient draft under all conditions. 27 is a valve which can either be moved to open up both passages 25 and 26 or close off the passage 26. Between the 70 ends of the port 26 is arranged the valve 28, which may be moved to either cut off the way through said port or the discharge from an air-supply pipe 29. 5 is the gas-supply pipe and 13 the valve controlling the flow of 75 gas therethrough. 30 is the air-supply pipe. 31 and 32 are the reversing-valves for the gas and air supply pipes, respectively. 12 is the pipe which connects the port 26 of the flue with the passage 5, and 33 is a valve controlling the way therethrough. During the 80 position of normal working of the furnace the various valves stand in the position shown in Fig. 7. In this arrangement both ports 25 and 26 act together as the flue. Upon reversing valve 13 is closed, valve 33 opened, and valves 27 and 28 arranged to shut off the way through port 26. The draft through port 25 draws the combustible gases in the 85 regenerative chamber through the furnace, being followed by the smoke and external air, the latter flowing in through the admission-port 29. As soon as the flame in the furnace is extinguished valve 33 is shut and the other valves opened. The cubical contents of port 26 between valves 27 and 28 should be at least as large as the volume of 90 gas which is to be pressed into the furnace from the regenerative chambers. The chamber between the valves 27 and 28 must not 95 be a proper smoke-channel, but might be shaped as a chamber of any form which as to its volume is large enough and at suitable places foreseen with suitable valves. Likewise another channel or chamber filled with 100 flue-gases may be used in lieu of the channel belonging to the furnace, substantially as described.

Having thus fully described my invention, what I claim as new, and desire to secure by 110 Letters Patent, is—

1. In a Siemens regenerative furnace, the flue for products of combustion, a passage between the gas-regenerative chambers and the flue, a cut-off in said passage, and means for 115 causing the gases to flow, previous to reversing the apparatus, from the flue through the said passage into the gas-regenerative chamber, whereby the flue-gases cause a displacement into the furnace of the combustible 120 gases contained in the gas-regenerative chamber, substantially as described.

2. In a Siemens regenerative furnace, the flue for products of combustion, a passage between the gas-regenerative chambers and the flue, a cut-off in said passage and means for 125 sucking the flue-gases, previous to reversing the apparatus, from the flue through the said passage into the gas-regenerative chamber, whereby the sucking action causes a displace- 130

ment into the furnace of the combustible gases contained in the regenerative chamber, substantially as described.

3. In a Siemens regenerative furnace, the flue for products of combustion, a passage between the gas-regenerative chamber and the flue, a cut-off in said passage, and means for mechanically impelling the flue-gas from the flue through the said passage into the gas-regenerative chamber previous to reversing the apparatus, substantially as described.

4. In a Siemens regenerative furnace, the flue for products of combustion, a passage between the gas-regenerative chamber and the

flue, and a suction and pressure device in 15 said passage for causing the gases to flow, previous to reversing the apparatus, from the flue through the said passage into the gas-regenerative chamber, substantially as described.

In testimony whereof I have signed my name to this specification, in the presence of two subscribing witnesses, this 24th day of February, 1905.

ADALB. KURZWERNHART.
